UNITED STATES PATENT OFFICE.

FRANK E. PARKS, OF DUQUESNE, PENNSYLVANIA.

APPARATUS FOR HANDLING PIT-SCRAP.

SPECIFICATION forming part of Letters Patent No. 723,723, dated March 24, 1903.

Application filed September 17, 1902. Serial No. 123,773. (No model.)

To all whom it may concern:

Be it known that I, FRANK E. PARKS, of Duquesne, Allegheny county, Pennsylvania, have invented a new and useful Apparatus 5 for Handling Pit-Scrap, of which the following is a full, clear, and exact description, reference being had to the accompanying drawings, forming part of this specification, in which—

10 Figure 1 is a vertical cross-section of an open-hearth furnace arranged in accordance with my invention. Fig. 2 is a top plan view of the mold or box, and Fig. 3 is a cross-section of the same.
15 My invention relates to the collecting and handling of the molten metal drippings from open-hearth steel-furnaces, in which furnaces the metal is tapped into the ladle by means of a trough or spout which extends 20 forwardly from the tap-hole, and after the metal is tapped out the spout is removed. Small amounts of the molten steel remaining in the furnace drip from the tap-hole into the pit beneath the spout. These drippings 25 ordinarily collect in this pit with the slag, and after an accumulation thereof the mold is lifted out and taken to a skull-cracker, where it is broken up into fragments small enough to be put in the charging-boxes. It 30 is then recharged into the open-hearth furnace. This method of handling the pit-scrap is laborious and is the cause of considerable trouble and expense.

My invention consists in a new apparatus 35 for handling these drippings; and it consists, broadly, in the combination, with the furnace and its metal-tapping spout, of an open mold separate from the spout, placed in the pit beneath and at a considerable distance below the metal-spout. This mold is 40 of such a size that the steel collecting in it will form a casting of such size as can be easily placed in the charging-box without breaking up, and the mold is of such a shape 45 that the casting can be stripped upwardly from it, the mold remaining in place. The mold is not secured permanently in position, but merely rests upon a suitable foundation, preferably with a slag-packing around 50 it, so that in case of any trouble resulting from an accident in casting the box can be picked out and removed by a crane.

Referring to the drawings, in which I show a preferred form of my apparatus, 2 represents a stationary open-hearth furnace, which 55 may be of any ordinary form, and 3 the metal tap-hole therefor.

4 is the refractory lined removable metal-spout, which leads from the tap-hole outwardly to a point where the metal directed 60 therefrom will fall into the ladle 5. This spout is shown as supported upon a removable bridge 6, extending between the sides of the fore pit, which is between the furnace and the main pit 7, in which the ladle sits. 65 The mold or box 8 to receive the drippings is set beneath the spout and in position to receive the drippings from the tap-hole. This mold I have shown as consisting of a single casting with a forming-cavity having 70 upwardly and outwardly diverging sides, the cavity having its longitudinal axis in line with the spout. The box is set upon a suitable foundation, which may be either the dirt floor of the pit or a support built thereon, and the box is preferably packed around 75 with loose lump cinder.

In tapping the furnace the metal flows out through the tap-hole and the spout and falls into the ladle in the ordinary manner. When 80 the furnace is practically dry, the spout is removed and the remaining drippings fall from the tap-hole into the box or mold to receive them. If the holes in the furnace-hearth are puddled after the heat, the steel 85 forced out of these holes will also flow out and drip into the box.

Before the heat is tapped a metal bar or piece of scrap with a hooked end is set in the mold with its end projecting out, so that the 90 drippings will congeal around the shank and embed it, and when the drippings have flowed out after the tapping of one heat the casting is pulled out of the mold by means of the projecting hook. This casting is then put in a 95 charging-box and charged into one of the open-hearth furnaces in the ordinary way. Any slag which falls into the mold with the steel, being lighter than the steel, separates therefrom and is easily removable from the 100 casting.

The advantages of my invention result from the use of a mold which will receive and shape the drippings and which forms a cast-

ing of a proper size for recharging into the furnace. This is a means of great economy, for the steel is so tough that when the drippings collect in large irregular masses on the bottom of the pit, as heretofore, it is extremely difficult to break them up into fragments suitable for recharging; but my invention enables the steel drippings at once to be replaced in the furnace in convenient size and shape for remelting. The placing of the box at a considerable distance beneath the spout is important, as otherwise an overflow of metal in the box would weld it to the bridge and necessitate a new bridge and breaking up of the mass, resulting in extra labor and expense. By placing the box at some distance beneath the spout if the box overflows the surplus metal merely runs into the pit; but the box is of such size that in ordinary practice it will more than contain the amount of drippings from a single heat. The box is not permanently secured, and hence in case of an accident in casting it can be easily removed and a new box supplied.

Many variations may be made in the form and arrangement of the box, spout, &c., without departing from my invention.

I claim—

1. The combination with an open-hearth furnace, of an open-top mold resting in the pit beneath the metal-spout and in position to receive the metal drippings, said mold being separate from the spout; substantially as described.

2. The combination with an open-hearth furnace, of a movable open-top metal-mold resting below and removed from the spout and in position to receive the drippings, said mold having an upwardly and outwardly diverging mold-cavity; substantially as described.

3. The combination with an open-hearth furnace having a metal tap-hole, of a removable spout leading outwardly therefrom, and an open-top mold separate from the spout set in the pit beneath the spout and in position to receive the metal drippings; substantially as described.

In testimony whereof I have hereunto set my hand.

FRANK E. PARKS.
